Attorney

UNITED STATES PATENT OFFICE.

FRANCIS H. H. REEDER, OF OGDEN, UTAH.

SHOE-POLISH CONTAINER.

1,322,342.

Specification of Letters Patent. Patented Nov. 18, 1919.

Application filed May 27, 1918. Serial No. 236,780.

To all whom it may concern:

Be it known that I, FRANCIS H. H. REEDER, a citizen of the United States, residing at Ogden, in the county of Weber and State 5 of Utah, have invented certain new and useful Improvements in Shoe-Polish Containers, of which the following is a specification.

This invention relates to improvements in receptacles and it is the principal object of 10 the invention to provide a novel shoe polish receptacle having a dauber or other form of polish applying device engaged therewith and a polishing cloth arranged thereon in a manner such as will permit the engagement 15 of the same with a shoe, thus rendering an exceedingly desirable and compact article and obviating the use of the ordinary blackening box or like device.

Other objects will be in part obvious and 20 in part pointed out hereinafter.

In order that the invention and the manner of its application may be readily understood by those skilled in the art, I have in the accompanying illustrative drawings, and 25 in the detailed following description based thereon set forth a preferred embodiment of the invention.

In these drawings:

Figure 1 is a top plan view of the im- 30 proved box,

Fig. 2 is a side elevation thereof partly in section,

Fig. 3 is a side elevation of the receptacle lid showing the manner in which the dauber 35 engaging fingers are formed thereon,

Fig. 4 is a similar view showing the dauber engaging fingers in bent form to receive the dauber, and

Fig. 5 is a fragmentary detail in perspective of the lid showing the arrangement of 40 the dauber receiving fingers thereon.

Having more particular reference to the drawings, in connection with which like reference characters will designate correspond- 45 ing parts throughout the several views, 1 represents the receptacle and 2 the lid there- of which are both formed of relatively thin sheet material. In this connection, it is to be noted that the receptacle and its lid are 50 formed or shaped to constitute an efficient form of handle which may be easily and firmly grasped by a user; the receptacle being provided with a beading or shoulder 3

adapted to be engaged by the lower marginal portion of the lid in order that the same 55 will be properly positioned with relation thereto when arranged over the same.

Arranged over the bottom of the receptacle 1 and secured thereto by some suitable adhesive or similar means is the shoe polishing cloth 4 of suitable material, said cloth being so arranged as to permit the same to be effectually engaged with a shoe or other object to be polished thereby.

Depending spaced fingers 5 and 6 are 65 formed integral with one marginal portion of the lid 2, preferably, at a point adjacent one end thereof and are adapted to be bent upwardly as shown in the Fig. 3 to a sub- 60 stantially horizontal position and then bent 70 upon themselves to provide annular dauber receiving elements, clearly shown in the Figs. 4 and 5. It of course will be understood that previous to the bending of the fingers 5 and 6 into annular form, the handle por- 75 tion of a suitable form of dauber 7 is ar- ranged adjacent the same, whereupon said fingers 5 and 6 are then bent in opposite directions about the same, thus forming an effectual connection between said handle 80 portion of the dauber and the receptacle lid 2; the lid, obviously, affording a handle for the dauber to facilitate the application of the polish to a shoe or other object. Fur- 85 thermore, it is to be also noted that the brush portion of the dauber is arranged to extend below the lower marginal portion of the lid 2 in order that the same can be effec- tually engaged with the polish arranged in the receptacle 1 and as equally well applied 90 to the surface of a shoe or other object to be polished thereby.

In using my improved device, the lid 2 is of course removed from the receptacle 1 and serves as a suitable handle whereby the 95 dauber 7 can be engaged with the polish. Subsequent to the application of the polish to the surface of a shoe or other object, the lid, if desired, can be replaced over the receptacle 1 and the receptacle then moved back 100 and forth over the surface of the shoe in a manner to cause engagement of the polish- ing cloth 4 therewith, thus effecting the de- sired polishing operation.

Attention is directed to the fact that by 105 forming the receptacle 1 and its respective

lid 2 in the peculiar manner herein shown, I am enabled to provide an effectual form of handle for the dauber 7 as well as the polishing cloth 4, thus materially facilitating the 5 use of the same by a person.

Of course, it is to be understood that other forms of means for connecting the dauber 7 to the lid 2 of the device may be substituted if desired, such as conditions or preference 10 may dictate.

Manifestly, the construction shown is capable of considerable modification and such modification as is within the scope of my

claim, I consider within the spirit of my invention.

I claim:

A device of the character described including a receptacle lid shaped to afford a handle, fingers formed integral with one marginal portion of the lid adjacent one 20 end thereof, and a dauber engaged by said fingers and secured to the lid.

In testimony whereof, I affix my signature hereto.

FRANCIS H. H. REEDER.
